(57) **CLAIM**

The ornamental design for a remote jack pack, as shown and described.

DESCRIPTION

FIG. 1 is a top, front, perspective view of a remote jack pack showing our new design;

FIG. 2 is a front view thereof;

FIG. 3 is a rear view thereof;

FIG. 4 is a left side view thereof, the right side view being a same image thereof;

FIG. 5 is a top plan view thereof, the bottom plan view being a same image thereof; and,

FIG. 6 is a top, front perspective view thereof, on a smaller scale, and in use condition.

The broken line shown in FIG. 6 is included for the purpose of illustrating environment and forms no part of the claimed design.
